UNITED STATES PATENT OFFICE.

GEORGE J. S. COLLINS, OF CHICAGO, ILLINOIS.

ROLLER-BEARING.

SPECIFICATION forming part of Letters Patent No. 595,696, dated December 21, 1897.

Application filed July 30, 1896. Serial No. 601,043. (No model.)

To all whom it may concern:

Be it known that I, GEORGE J. S. COLLINS, of Chicago, in the county of Cook and State of Illinois, have invented certain new and useful Improvements in Roller-Bearings; and I do hereby declare that the following is a full, clear, and exact description thereof, reference being had to the accompanying drawings, and to the letters of reference marked thereon, which form a part of this specification.

This invention relates to improvements in roller-bearings and refers more specifically to means for housing and separating the balls or roller elements in such bearings. In a previous application, Serial No. 576,101, filed January 20, 1896, I have described and claimed a construction wherein the roller elements traveled in the same direction with respect to the bearing, which action is accomplished by means of roller-separating devices interposed between adjacent parts of the main supporting-roller elements.

My present invention relates more particularly to means for connecting the several separating devices and also means whereby all the roller elements are rotatably held in a housing and are thus capable of being bodily removed from the journal simultaneously without disturbing the relative position of said roller elements.

The invention also has reference to a novel arrangement and disposition of the angles of the bearing-surfaces of the cones and ball-cup, whereby relative movement of the axle with reference to the bearings is prevented and also an improved bearing secured.

The nature of the invention and its advantages will be more fully understood by reference to the illustrations and the subjoined descriptions, and will be pointed out in the appended claims.

For convenience the illustrations of my improvements are shown as embodied in a bearing for a bicycle-wheel; but it is obvious that the invention may be practically embodied without substantial change to any kind of bearing for which as a class roller-bearings are adapted.

In the drawings, Figure 1 illustrates a central vertical sectional view of a bearing embodying my invention. Fig. 2 is an end view

of the same with the cap removed. Fig. 3 is a side view of the ball or roller element housing shown in Fig. 2. Fig. 4 is a plan view of 55 a modified form of housing for the ball or roller elements. Fig. 5 is a side elevation of the same. Figs. 6 and 7 are plan views of modified forms of the housing for the ball or roller elements. Fig. 8 is a perspective fragmentary view of the form of housing shown in Fig. 6. Fig. 9 is a sectional view of the bearing, showing the application of the modification of housing shown in Fig. 6. Fig. 10 is a sectional view of a bearing, showing the 60 application of the modification of housing 65 illustrated in Fig. 7.

Referring to the construction shown in Fig. 1, the letter A designates as a whole the hub of a wheel of tubular form and provided near 70 its end with a cup-bearing B, the latter having a central opening b at its inner end, through which the axle C projects. The inner or bearing surface of the cup B (lettered b') is shown as formed at an angle of seven and one-half 75 degrees with respect to the longitudinal axis of the axle C. D is a cone secured upon the axle C by screw-threads in a familiar manner and having a conical or flaring bearing-surface d, shown as arranged at an angle of 80 forty-five degrees with respect to the longitudinal axis of the axle C. The cone D has an exteriorly-screw-threaded hub d', and upon said hub I secure a nut or ring D', which is provided with a conical or tapered face d'', 85 which is shown as formed at an angle of thirty degrees from the longitudinal axis of the axle C. E E are main balls or roller elements resting in the race formed between the surfaces d d'' and upon which the surface b' of 90 the cup-bearing B rests. I have determined after much experimentation that a three-point ball-bearing in which the outer bearing-surface is formed at an angle equal to one-half of the difference between the angles of the 95 inner bearing-surfaces produces the very best results, other things being equal, affords less opportunity for cramping, and diminishes the friction as well as the wear upon the parts, and I shall therefore make a claim to this 100 specific construction separately as well as in combination with the other features of my invention herein disclosed. C' is a cap secured upon the screw-threaded end c of the

axle C. For convenience of illustration and description I have shown the angles of thirty degrees, forty-five degrees, and seven and one-half degrees as applied to the axle-bearingsurfaces and cup-bearing surfaces, respectively.

Referring now to Figs. 4 and 5, it will be observed that the roller elements E are rotatably confined between separating devices, which latter consist of rollers F, arranged in this instance parallel to the bearing-surface b' of the cup B. The several separating elements F are each rotatably mounted upon a pin f, the ends of which project through suitable apertures in two side plates F', which constitute the sides of the housing for the roller elements. The outer margins of the plates F' are held at suitable distances apart by spreading blocks or pins f'.
 20 By reference to Figs. 4 and 5 it will be noticed that the roller elements E are of greater diameter than the width of the housing, and hence project through suitable slots or apertures f², one of which is positioned between each pair of separators F. It will also be noted that the distances between adjacent separators F and the relative distances between their bearing-surfaces and the outer margins of the plates F' with relation to the diameter of the roller elements are such as to cause the latter to extend beyond the outer margins of the plates F'. It is therefore apparent that the plates F' have no bearing-points which can in any way interfere with the engagement of the roller elements E and their operation upon the bearing-surfaces with which they are designed to engage.

As shown in Fig. 1, the portion of the roller element E that projects between the plates F' and their outer margins engages the conical bearing-surfaces b' of the cup B, while those surfaces of the elements E which project through the apertures f² of the plates F' engage the surface d and d² of the cone D and the nut d', respectively. As explained in my said former application, the separating elements F enable me to rotate all the roller elements E in the same direction and in the direction in which the bearing-surfaces b' of the cup B is traveling, whereby all but the rolling friction is avoided.

Referring to the construction shown in Figs. 3 and 2, it will be noted that it is precisely the same as that shown in Figs. 4 and 5, with the exception that in the latter the separating elements F are substantially of the same length as the spreading blocks or pins f', and hence the plates F' are substantially parallel, while in Figs. 1, 2, and 3 the separating elements F are very much shorter than the spreading pins or blocks f, and hence the inner portions of the plates F', carrying the separating elements or rollers F, are bent, as shown at f³, so as to snugly engage the respective ends of said separators F, the pins f passing through the separators and through the inwardly-

bended portions of the plates F', as shown in the drawings.

Referring now to the construction shown in Figs. 6, 8, and 9, it will be noticed that the housing in its general arrangement is the same as in the two forms previously described, it consisting of two side plates F', each scalloped at its inner margin to form apertures or recesses f². To the inner ends of those portions 70 of the plates F' between said spaces or apertures f² the separators F are secured, as before described. The plates F' are also bent; but in this instance they are so bent as to bring the outer margins f⁴ against each other, 80 and therefore the separator blocks or pins f' of the formerly-described construction now become rivets or pins f⁵. This construction of housing I find convenient to use where a bearing like that shown in Fig. 9 is employed. 85 Said bearing consists of the shell or hub G, having an enlarged and outwardly-directed portion G', with interior surfaces g g', the latter being screw-threaded and the former, g, being given a suitable angle to form a bearing-surface. A nut H, provided with a conical bearing-surface h, is secured to the hub G, engaging the screw-threaded portion g' in a familiar manner, the portions g and h forming a conical two-part bearing-surface for the 90 roller elements E. In this instance the axle C is provided with an integral cone C². The cone D is secured to the axle C in the usual manner, as is also the cap C'. It will be observed in this form of bearing that the roller element E has four tangential bearing-points. It may or may not be convenient to make the cone D, as well as the cone C², integral with the axle C. At any rate it is more convenient to arrange the form of housing for the 105 roller elements so that it shall not approach too closely to the conical surfaces thereof, and for this reason I find it convenient to join the outer margins of the plates F', as indicated. A convenient space h is provided for the free 110 movement of said outer margins of the plates F' by reason of the fact that the adjacent margins of the conical surfaces h and g may be cut away, as shown.
 115 In some instances I may find it desirable to use the form of bearing shown in Fig. 10, which is the same construction as that shown in Fig. 9, with the exception of the cones D and C². As shown in this figure, there are two cones I and I', having a bearing-surface 120 i i', respectively, secured upon the axle C by screw-threads in a familiar manner. The bearing-surfaces i i' of these cones are separated by an extension i² on the cone I', which extension is of reduced diameter, thereby 125 forming an annular groove i³ in the bottom of the ball-race that is formed by the adjacent bearing-surfaces i i' of the cones. The housing for the roller elements consists of the two plates F', scalloped exteriorly to form apertures f², as before, in which apertures the roller elements E are placed. These separator-

rollers F to support the roller elements E are positioned as before, but the plates F' are brought together near their inner margins and are secured by rivets f⁶. The extreme inner margins of the plates F' are bent outwardly at right angles, as shown at f⁷, and thus constitute an interior annular bearing-ring or bearing-surface for the housing. The combined width of these flanges, as well as the interior diameter of the plates between the flanges, is such that the ring or bearing-surface is adapted to fit loosely, as shown in Fig. 10, within the annular groove v³ in the bottom of the ball-bearing race. While it is intended that the ring shall not be loose in said groove and that the construction will be such as will tend to steady the housing in position, yet it is to be understood that the proportions are to be such that there shall be no substantial amount of friction—in other words, that the housing shall rotate with perfect freedom.

It will be obvious that with the exception of the constructions shown in Figs. 7 and 10 the roller elements may be removed bodily from the bearing or hub in the housing-frame by the two plates F'.

I have above described several modifications of my improved housing for rollerbearings, and it will be manifest therefrom that other modifications will suggest themselves to the mind of the skilled mechanic in applying the roller elements embodying my invention to other forms of bearing than those illustrated, and I desire it to be distinctly understood that all such modifications are to be embraced within the scope and spirit of my invention, the essential features of which are stated in the claims hereto appended.

40 I claim as my invention—

1. The combination with an axle, of a cone thereon having a bearing-surface arranged at an angle to the longitudinal axis of the axle, a nut on said axle provided with an oppositely-arranged bearing-surface, said two bearing-surfaces being arranged on different angles and forming a ball-race, a ball-cup provided with a bearing-surface opposed to said oppositely-arranged surfaces and formed at an angle with respect to the longitudinal axis of the axle equal to one-half the difference between the angles of the other two bearing-surfaces, a plurality of roller elements, a roller-separating device between each pair of roller elements, and means for securing each roller-separating device with its longitudinal axis parallel with the plane of the bearing-surface of the cup-bearing, substantially as described.

60 2. The combination with an axle, of a cone thereon having a bearing-surface arranged at an angle to the longitudinal axis of the axle, a nut provided with a bearing-surface arranged opposite to the bearing-surface of the cone and at a different angle, said two bearing-surfaces forming a ball-race, a ball-cup provided with a bearing-surface opposed

to said oppositely-arranged surfaces and formed at an angle with respect to the longitudinal axis of the axle equal to one-half the difference of the angles between the cone and nut, a plurality of roller elements, roller-separating devices, one between each pair of roller elements located inside of a line passing through the center of the roller elements and means for securing said parts in operative relation, substantially as specified.

70 3. The combination with an axle, of a cone thereon having a bearing-surface arranged at an angle to the longitudinal axis of the axle, a nut provided with an oppositely-arranged bearing-surface, said two bearing-surfaces being arranged at different angles and forming a ball-race, a ball-cup provided with a bearing-surface opposed to said oppositely-arranged surfaces and formed at an angle to the longitudinal axis of the axle equal to one-half the difference between the angles of the cone and nut, a plurality of roller elements, roller-separating devices, one between each pair of roller elements, and means for securing said parts in operative relation, comprising a pair of housing-plates between which the separating devices are secured at suitable intervals, and having suitable apertures therein for the reception of the roller elements, substantially as described.

75 4. In a ball-bearing, a housing for the roller elements comprising two annular plates, means for securing the same together, and at a suitable distance apart, a plurality of roller elements located intermediate of the plates, and a rotatable ball-separating device between adjacent roller elements and located inside of a line passing through the centers of the roller elements.

80 5. In a ball-bearing, a housing for the ball or roller elements comprising two annular or ring plates, means for securing the same together at suitable distances apart, a plurality of roller elements located intermediate said plates between oppositely-arranged recesses therein, a rotatable ball-separating device between adjacent roller elements and recesses, substantially as described.

85 6. In a ball-bearing, a housing for the ball or roller elements, comprising two annular plates, means for securing the same together but at a suitable distance apart, a plurality of roller elements located intermediate said plates between oppositely-arranged recesses therein, and a rotatable ball-separating device between adjacent roller elements, said roller elements being so located in said recess that their inner surfaces will lie inside of a circumferential line passing through the ball-separating devices.

90 7. In a ball-bearing, a housing for the ball or roller elements, comprising two annular ring-plates, means for securing the same together but at a suitable distance apart, a plurality of roller elements located intermediate said plates between oppositely-arranged recesses therein, and a rotatable ball-separat-

- ing device between adjacent roller elements, the diameter of said roller elements being greater than the distance between adjacent separating devices whereby they may be simultaneously removed from or placed in the bearing.
8. A housing for the roller elements of a ball-bearing comprising two ring-plates, a plurality of ball-separating devices rotatably secured at intervals between the plates at or near their inner margins, said rings being provided with a socket or recess between each separating device, a plurality of roller elements in said sockets and means for securing the plates at a suitable distance apart whereby said roller elements may partially project beyond the plane of the outer surfaces of said plates and also project peripherally between them as and for the purpose specified.
9. In a ball-bearing, a housing comprising two ring-plates having suitable corresponding recesses, roller-bearing elements in said recesses, a roller-separating device between each pair of roller elements, and means for

securing said parts in operative relation comprising rivets passing through adjacent and engaging marginal parts of the ring-plates, each plate having an annular bend therein, substantially as and for the purpose specified.

10. In a roller-bearing, the combination with an axle provided with suitable bearing-surfaces, a hub provided with a ball-cup and roller elements located in the race formed thereby, ball-separating devices between the roller elements of a housing for confining the roller elements whereby said housing and roller elements may be removed from the bearing without disturbing the relation of the balls to each other.

In testimony that I claim the foregoing as my invention I affix my signature, in presence of two witnesses, this 23d day of July, A. D. 1896.

GEORGE J. S. COLLINS.
